ATTORNEYS.

UNITED STATES PATENT OFFICE.

NICOLAS BENOIT GRILLET, OF NEUILLY, FRANCE, ASSIGNOR TO SOCIÉTÉ POUR LA FABRICATION DE LA SOIE "RHODIASETA," OF PARIS, FRANCE.

APPARATUS FOR THE MANUFACTURE OF ARTIFICIAL SILK.

Application filed September 24, 1926, Serial No. 137,627, and in France October 1, 1925.

In my U. S. Letters Patent No. 1,571,474, granted the 2nd February, 1926, I have described methods permitting to ensure, in a group of cells intended for dry spinning of artificial threads, the regularity of the heating of the gaseous atmosphere and the uniformity of the flow of the said atmosphere for all the cells of a group of cells under consideration. By means of these methods, the regulation of the heating and of the gaseous flow is performed practically automatically, each of these regulations in each case being simultaneous for all the cells employed in the production of the same grade of silk.

The arrangement described in Patent No. 1,571,474, for obtaining the uniform regulation of the heating belongs to the general type of "series" circulation of the heating fluid through the successive elements of each group constituted by the whole of a number of neighbouring cells.

In certain arrangements of cells, it may be advantageous to obtain the heating of successive individual cells by having recourse to an arrangement for "parallel" circulation, and I have sought to obtain, in this case also, by a practically automatic method, the uniform regulation of the heating in the cells of a group or of several groups manufacturing the same product.

In such a system, the heating elements of a group are served by as many branch pipes as there are cells in the group, said branch pipes issuing from an inflow collector, and these heating elements are individually connected to an outlet collector.

The inlet collectors of the groups are themselves branched on the main pipes which connect them to the source of heat. The outlet collectors are connected to the main pipes for the exit of the fluid which, preferably, goes again through the cycle after being re-heated.

The difficulty met with in this type of circulation is not so much that of maintaining a uniform temperature along the whole length of the collectors feeding the individual heating elements; this can be easily attained by adapting, for the general plan of the installation, dispositions as symmetrical as possible, by carefully lagging the pipes, by causing a communication with the source of the heating fluid at both the extremities of the collector, or even at intermediate points, if necessary, etc.

The real difficulty to surmount in order to obtain the regularity of the heating in the case of a "parallel" circulation is that of obtaining a uniform flow of the heating fluid through the various individual elements.

According to this invention, the regularity of flow of the heating fluid through the individual elements is obtained by supplying to the circulation of this fluid in the heating elements by the methods described in Patent No. 1,571,474 for the circulation of the gaseous atmosphere in the cells.

If the heating fluid is supposed to flow under pressure in the system under consideration, it is first necessary that the pressure should be the same at all the points where an individual branch pipe supplying one element leaves one of the collectors belonging to the said system. For this, it is important that all the pipes conveying the fluid from the point where pressure is applied to it to the individual branch pipes, that is, all the main and secondary collectors, should be designed with a very large diameter, so as to render negligible the losses of head along this distance. The same precaution must be observed respecting the dimensions of the secondary and main collectors receiving the fluid issuing from the individual elements.

Owing to these measures, if the connecting pipes and the individual heating elements are identical both in construction and in the manner in which they are disposed, the conditions of uniformity of flow in the individual elements will be much nearer obtainment. For an installation of given dimensions, a working pressure in the system under consideration will correspond to each desired rate of flow.

In fact, however, it will be difficult to prevent the heating elements from having small differences of construction, or to prevent certain elements from suffering accidental modifications in the course of working. The result would be differences in the "absolute resistance" of the elements, and differences in the rate of flow under the same pressure would follow.

In order to have every guarantee of uniformity in the rates of flow of the heating fluid in spite of these possibilities, it will be necessary to maintain in the system a much higher pressure than that necessary for ensuring the required rate of flow, and to place on the path of the heating fluid a device caus-

ing a substantial loss of head, such as a thin plate provided with a small hole of a predetermined diameter, a constriction of the piping of predetermined length and diameter, etc., which creates a notable loss of head, the influence of which is great with respect to the loss of head in the heating element itself and to the losses of head in the piping system, a given rate of flow corresponding to a given pressure in an arrangement of given dimensions.

All these devices creating a loss of head, placed on the heating elements belonging to the cells manufacturing a similar type of thread, are identical, and the rate of flow of the heating fluid will be caused to vary simultaneously in all these elements by varying the pressure in the system.

Preferably, these devices will be removable, so that, in case of need, all the devices supplying the heating elements of a group of cells manufacturing a similar product may be altogether replaced by other arrangements all identical to one another, creating a lesser or a greater loss of head for a similar pressure, that is, a greater or a lesser rate of flow, respectively.

The above explanations relate to the case in which the motion of fluid is caused by pressure, but the reasoning would be similar and the arrangements to be adopted would be the same if the movement of the fluid were caused by suction.

It is well understood that the method according to the present invention is applicable whatever may be the heating fluid employed, water, steam, any gas, etc., and whatever may be the type of heating element traversed (fin tube, coil, jacket).

A single heating system of the type described may be contemplated for each spinning cell, or, on the contrary, several systems may be used, fed, for example, by fluids of different temperatures, and heating different zones of the cell, for example, on the one hand the region near the dies and on the other hand the region near the aperture through which the filaments issue.

The heating elements may heat either the cell itself, or any individual flow of atmosphere intended for the cell, before its introduction into any desired region of the cell.

The present invention is also applicable to the case when, instead of heating a zone of the spinning cell, it is, on the contrary, required to cool it, the reasonings set forth above being evidently as suitable in this case as for heating.

In the appended drawings, Fig. 1 represents diagrammatically an arrangement in which the spinning cells *a*, *a*, *a*... of a same métier are heated by hot water jackets *b*, *b*, *b*...

The hot water arrives by the main piping *c* in the branch pipings *d* feeding the individ-

ual cells, and in which are disposed the perforated diaphragms *e*. The heating water, after percolating through the jacket, leaves by the pipes *f* opening into the exhaust piping *g*.

Fig. 2 shows an arrangement in which each spinning cell *a* is heated by two water jackets *b*₁ and *b*₂, each of which is part of a system similar to that shown in Fig. 1, so that the upper and the lower portions of the cell are heated at different temperatures, the upper one by the arrangement *c*₁, *d*₁, *e*₁, *b*₁, *f*₁, *g*₁, and the lower one by the arrangement *c*₂, *d*₂, *e*₂, *b*₂, *f*₂, *g*₂.

As an example, it may be stated that, in a given apparatus, the piping *c* had a diameter of 10 centimetres and the loss of head between the two ends of the piping was found to be 2 millimetres of water, while the diaphragms *e* had orifices 2 millimetres in diameter causing a head of 20 centimetres of water, hundred times greater than in the main piping. In these conditions, the operation of the arrangement was found exactly as set forth.

What I claim and desire to secure by Letters Patent is:—

1. In the manufacture of artificial threads by "dry spinning", means for adjusting uniformly the temperature of the gaseous atmosphere in all the cells by means of temperature-controlling elements connected in parallel and identical for all the cells, means being provided for producing a fall of pressure, identical in each temperature-controlling element, by devices, interchangeable but not individually adjustable, identical for all temperature-controlling elements, causing a substantial loss of head thereat, the said temperature-controlling elements of individual cells being connected in parallel between main piping designed for a rate of flow of the temperature-controlling fluid greatly in excess of that required, so as to render the loss of head in said pipings negligible.

2. In the manufacture of artificial threads by "dry spinning", means for controlling the temperature of the gaseous current in all the cells, as claimed in claim 1, characterized in that more than one temperature-controlling element is used in each cell, the temperature-controlling fluid in said elements being at a different temperature, so as to obtain a different temperature in different portions of the cell.

3. A spinning apparatus for the manufacture of artificial threads by dry spinning comprising a plurality of spinning cells, means to circulate a heating medium to heat said cells, and means to control the temperature of each of said cells, said means causing a substantial loss of head thereat and being connected in parallel between said heat-circulating means.

4. A spinning apparatus for the manufac-

- ture of artificial threads by dry spinning comprising a plurality of spinning cells, piping providing the circulation of a heating medium without any substantial loss of head therein, means for controlling the temperature of each of said cells, said means causing a substantial loss of head thereat and being connected in parallel between said piping.
- 10 5. A spinning apparatus for the manufacture of artificial threads by dry spinning comprising a plurality of spinning cells, means to circulate a heating medium to heat said cells, a plurality of means to control the 15 temperature of each cell at various portions thereof, said means causing a substantial

loss of head thereat and connected in parallel between said heat-circulating means.

6. A spinning apparatus for the manufacture of artificial threads by dry spinning 20 comprising a plurality of spinning cells, piping providing the circulation of a heating medium without any substantial loss of head therein, a plurality of means to control the temperature of each cell at various 25 portions thereof, said means causing a substantial loss of head thereat and connected in parallel between the said heat-circulating means.

In testimony whereof I have signed my 30 name to this specification.

NICOLAS BENOIT GRILLET.
